UNITED STATES PATENT OFFICE.

LEANDER M. NUTE, OF GREAT FALLS, NEW HAMPSHIRE, ASSIGNOR OF ONE-FOURTH TO GEORGE MOORE, OF BERWICK, MAINE.

BOOT OR SHOE.

SPECIFICATION forming part of Letters Patent No. 431,990, dated July 8, 1890.

Application filed April 23, 1890. Serial No. 349,165. (No model.)

To all whom it may concern:

Be it known that I, LEANDER M. NUTE, a citizen of the United States, residing at Great Falls, in the county of Strafford and State of 5 New Hampshire, have invented certain Improvements in Boots or Shoes, of which the following is a full, clear, and exact description, reference being had to the accompanying drawings, making part of this specification, 10 in which—

Figure 1 is a perspective view of a shoe, a portion of the vamp being turned back to show one of the guide-strips which form the subject of my invention. Fig. 2 is a vertical 15 transverse section of the heel portion of the shoe.

In the ordinary operation of putting counters into boots or shoes, the upper edge of the counter, which is introduced between the lining and the vamp or foxing, is liable to be pushed up beyond the lower edge of the top of the shoe, so as to project upon the inner side of the same, thereby displacing the lining and producing a hard stiff edge or ridge on the 25 inside of the heel portion of the shoe, which is uncomfortable to the wearer and renders the boot or shoe unsalable.

To remedy this difficulty is the object of my invention, which consists in fastening to 30 the lower edge or bottom of the top of the shoe, on each side of the same, a strip of leather or other suitable material, which extends down between the lining and the vamp or foxing, and serves as a guide for the upper 35 edge or portion of the counter, which is introduced between the outer side of said strip and the vamp or foxing, whereby the upper portion of the counter is kept out of contact with the lining and prevented from projecting inward and producing a stiff edge or ridge 40 on the inside of the shoe, as hereinafter more particularly set forth.

In the said drawings, A represents the vamp of the shoe, B the top portion of the same, 45 and C the lining, all of the ordinary construction.

In the operation of fitting or stitching the shoe before vamping, a narrow guide-strip D, of leather or other suitable material, is secured, by stitching or in any other suitable

manner, to the lower edge or bottom of the top portion B of the shoe on each side of the "heel-seat." The vamp A is then stitched onto the top portion B, as usual, its upper edge completely covering and concealing the 55 upper edges of the guide-strips D. The counter G is then applied, its upper edge or portion being placed between the outer side of the guide-strip and the vamp, as seen in Fig. 2, and forced up as far as permitted by the 60 line of stitching f, which unites the vamp with the top B, after which the shoe is lasted in the ordinary manner. The strips D thus interposed between the counter and the lining on opposite sides of the heel-seat effect- 65 ally keep the upper edge of the counter away from the lining and render it absolutely im- 70 possible for it to form a ridge or hard edge on the inside of the shoe, as heretofore, whereby much loss and annoyance to the manufac- 75 turer, caused by carelessness and imperfect work, are avoided, as the workman has only to see that the edge of the counter is placed between the vamp and the strip D, when the latter will guide it into place and prevent it 80 from being pushed up beyond the line of stitching f. Furthermore, the edge of the counter is held so firmly between the strips D and the vamp that it cannot curl up or project inward, as heretofore, and consequently 85 it will retain its original shape for a much greater length of time.

What I claim as my invention, and desire to secure by Letters Patent, is—

In a boot or shoe, the combination, with the 85 vamp or foxing A and the lining C, of the top portion B, having on each side of the heel-seat a guide-strip D, secured to its bottom or lower edge and extending down between the lining and said vamp or foxing, and the coun- 90 ter G, having its upper edge or portion placed between the said guide-strips D and the vamp or foxing, substantially as and for the purpose set forth.

Witness my hand this 19th day of April, 95 A. D. 1890.

LEANDER M. NUTE.

In presence of—

P. E. TESCHEMACHER,
HARRY W. AIKEN.
